UNITED STATES PATENT OFFICE.

GORDON M. BLANCHARD, OF SPIRIT LAKE, IOWA.

MUSIC-LEAF TURNER.

1,201,680.

Specification of Letters Patent.

Patented Oct. 17, 1916.

Application filed January 18, 1916. Serial No. 72,789.

To all whom it may concern:

Be it known that I, GORDON M. BLANCHARD, a citizen of the United States, residing at Spirit Lake, in the county of Dickinson, State of Iowa, have invented certain new and useful Improvements in Music-Leaf Turners; and I do hereby declare the following to be a full, clear, and exact description of the invention, such as will enable others skilled in the art to which it appertains to make and use the same.

This invention relates to new and useful improvements in music leaf turners.

It is the object in general of the present invention to improve the structure and efficiency of devices of this character, and it is more specifically the object to provide a music leaf turner to which the leaves of music may be very readily attached and quickly set for operation, and operated; the device being of such light and compact structure that a plurality of such turners may be provided so that the various pieces of music to be played may be each associated with a turning mechanism.

It is further an object to provide such a device comprising a relatively simple structure permitting manufacture at a comparatively low cost.

With the above and other objects and advantages in view, the invention resides more particularly in the novel combination, formation and arrangement of parts as more fully described hereinafter and pointed out in the appended claims.

Reference is had to the accompanying drawings, wherein similar characters of reference designate corresponding parts throughout the several views, and in which: Figure 1 is an elevational view of a music leaf turner constructed in accordance with the present invention, Fig. 2 is a top plan view thereof, Fig. 3 is an end elevation, Fig. 4 is a central vertical sectional view through the device on the line 4—4 of Fig. 1, Fig. 5 is a detail sectional view on the line 5—5 of Fig. 1, and Fig. 6 is a perspective view of one of the releasing pawls.

Referring now more particularly to the accompanying drawing, the body of the improved device comprises a frame formed of the top and bottom metallic strips 5 and 6 respectively and the end strips 7 and 8 respectively, the strip 8 being disposed at the

right hand end of the device as shown on 55 the drawings. Extending downwardly from the bottom strip 6 are leg portions 9 which are curved rearwardly and then upwardly and faced with felt or the like 10 to prevent injury to the piano structure, 60 these leg portions holding the lower portion of the body spaced above the retaining flange of the music rack of the piano on which the device is adapted to be placed, so that the turning frames may freely swing. 65 In the structure, as shown, two of these turning frames 11 and 12 respectively are shown, each comprising top and bottom bars and an outer end bar and these frames are centrally pivoted to the body frame by pivot 70 pins 13 which are held by bracket members 14 secured on the top and bottom strips of said body.

The attaching ends of the frame 11 are reduced in an outwardly offset manner and 75 bent at 15 around the pivot pins outwardly of the brackets and the attaching ends of the frame 12 are reduced in an inwardly offset manner and bent at 16 around the pivot pins inwardly of the brackets so that 80 the frames may swing to lie substantially parallel. For resiliently urging these frames to the left, a bar 17 is provided transversely at the central portion of the main frame and having its ends bent laterally and 85 then inwardly at 18 and secured to the rear of the frame. A second bar 19 is bolted to this bar and has its intermediate portion bent at 20 to provide a bearing member and has its ends bent inward at 21 and a shaft 90 22 is passed through the bearing 20 and the portions 18 and 21. Springs 23 are coiled about the shaft at the sides of the bearings 20 and have their inner ends secured to the said bearing and their outer ends extended 95 and secured to the frames 11 and 12. The means for holding these frames to the right so that they may be successively released comprises a member 24 pivoted to the lower portion of the end strip 8 of the main frame 100 and bent in substantially in U-shape to have its free arm engage over the frame and having the extremity of said free arm bent backwardly to form an actuating finger 25 whereby the member may be swung to release the frame. A similar member 26 of relatively wider bight is provided for engaging the frame 12. These members are

adapted to be actuated in any desired manner as by the strings 27 secured to their respective fingers.

What is claimed is:

- 3 1. A music leaf turner comprising a body frame, a bar connecting the side members of said frame inwardly from their ends, a second bar secured to the first mentioned bar and bent intermediate its ends and at its ex-
- 10 tremities to form bearing portions, a shaft supported by said bearing portions, springs encircling said shaft between said central and end bearing portions and each being secured at one end to one of said bars, sheet
- 15 supporting frames pivoted to said body frame, the opposite ends of said springs being secured one to each of said frames, and means for releasably holding said sheet frames against the tension of said springs.
- 20 2. A music leaf turner comprising a body frame, a bar, the ends of said bar being bent

forwardly and then inwardly to provide supports, the said body frame having its side bars secured to said supports, a second bar secured to the forward face of the first bar and being bent forwardly intermediate its ends and at its extremities to provide spaced bearing portions, the said ends lying beneath said supports, a shaft extending through said bearing portions and through the bent ends of said first bar, springs on said shaft, sheet frames pivoted to swing on said body frame, said springs being connected to said sheet frames, and means for releasably holding said frames against the tension of said springs. 25 30 35

In testimony whereof, I affix my signature, in the presence of two witnesses.

GORDON M. BLANCHARD.
